UNITED STATES PATENT OFFICE.

CHRISTIAN CASPAR SCHWANER, OF WINTERSET, IOWA, AND HARRY SHAFER BOLLINGER, OF CHICAGO, ILLINOIS.

HAME-TUG AND TRACE-FASTENING.

SPECIFICATION forming part of Letters Patent No. 308,931, dated December 9, 1884.

Application filed May 2, 1884. (No model.)

To all whom it may concern:

Be it known that we, CHRISTIAN C. SCHWANER, of Winterset, Madison county, Iowa, and HARRY S. BOLLINGER, of Chicago, Cook county, Illinois, have invented an Improved Harness Hame-Tug and Trace-Fastening, of which the following is a specification.

Our improvement relates to the manner of forming eyes in the hame-tug, and a hook or buttoning device on the end of a trace adapted to be detachably inserted in the eyes, and the trace thereby adjustably connected with the hame-tug.

Our invention consists in the construction and combination of a hame-tug having eyes and a contractile and expandable button and trace-fastening device, as hereinafter fully set forth.

Figure 1 of the accompanying drawings is a top view, and Fig. 2 a transverse section, of a hame-tug having eyes and loops formed of one piece of metal and one leather strap. Fig. 3 is a top view, and Fig. 4 a transverse section, of a hame-tug formed of two overlapping metal pieces and a leather covering on the lower piece. Fig. 5 is a longitudinal section of the end of Fig. 3, showing a locking device for detachably connecting the two overlapping metal pieces without rivets or screws. Fig. 6 is a top view showing a trace detachably and adjustably connected with a hame-tug having a cock-eye hame-clip flexibly connected with its front end. Fig. 7 is a perspective view, and Fig. 8 a vertical longitudinal section, of a clip having a hook and buttoning device adapted to fasten the end of a trace to the hame-tug having eyes.

Jointly considered these figures clearly illustrate the construction and operation of our complete invention.

A and B are metal plates fastened together in a manner similar to that shown in the United States Letters Patent No. 286,230, issued October 9, 1883. The base-plate A has a series of perforations or eyes, 1 2 3, in the line of its center, and annular flanges C on the upper side of each eye, as clearly shown in Fig. 4. The upper plate, B, has flanges on its edges and under side and flanged perforations in its center corresponding in size and number with the series of eyes 1 2 3 and their annular

flanges C in the plate A, that are designed to project through the plate B.

D is a hook formed on the rear end and center of the top plate, B, to project through a corresponding opening in the end of the plate A, as clearly shown in Fig. 5, for the purpose of locking the two plates together and dispensing with a screw.

F is a loop formed on the rear end of the plate A.

G (shown in Figs. 1 and 3) is a loop formed on the front end of the plate A for the purposes of producing a long and jointed hame-tug, as represented by Fig. 3.

H represents a cockeye-clip hinged to the end of a hame-tug adapted for a slip-tug harness.

J is a leather covering drawn over the base-plate A and fastened by means of stitches or in any suitable way, and then covered and its raw edges concealed by means of the top plate, B, in such a manner that the flanges on the under side and edges of the top plate will press upon the leather and form a tight joint and finished appearance.

To connect the top plate with the leather-covered base-plate we simply slip the hook D through an opening in the base A and under the base of the loop F, and then lay it upon the covered base-plate A in such a manner that the annular flanges C will project upward through the corresponding flanges in the plate B. By then inserting a single screw, K, in the overlapping front ends of the two metal plates the hame-tug is completed and ready for use.

L represents a clip adapted to be fixed to the end of a trace by means of rivets in a common way.

M is a hook extending at right angles from the front end and under side of the clip. It is semicircular and has an open chamber, N, adapted to receive a latch, and a spring to operate the latch.

P is a latch pivoted in the hook. Its lower end has a flange, R, corresponding with a similar flange on the lower end of the hook M, and a round head, S, at its top, that projects above the front of the clip.

T is a wire spring fixed to the pivot V, that connects the latch with the hook in such a

manner that it will, in its normal condition, hold the lower end of the latch away from the hook to increase the circumference of their flanges, which serve as a button in the eyes of 5 the hame-tug to keep the trace connected with the hame-tug.

Annular shoulders formed in the lower edges of the eyes or flanges C engage the flanges R of the latch and hook and allow the leather to 10 remain flat against the plate A.

Figs. 1, 2 show a modified form of our hame-tug, in which the plate B is provided with laterally-projecting perforated ears at its ends and opposite sides, adapting it to be riveted 15 upon a leather strap that will yield, as indicated by dotted lines in Fig. 2, when the buttoning device on the end of the trace is inserted in one of the series of eyes 1 2 3, as required, to adjustably connect a trace with a 20 hame-tug.

We claim as our invention—

1. In a hame-tug, the combination of a metal plate, A, having a series of perforations, 1 2 3, and annular flanges C, extending vertically 25 from said perforations, a metal plate, B, having flanges extending downward on its edges, and perforations adapted to admit and engage the flanges C, and a leather covering extending over the under side of the plate A and 30 under the edges of the plate B, as and for the purposes stated.

2. A metal plate, B, having a locking-hook, D, in combination with a base-plate in a hame-tug having an opening adapted to admit the hook, substantially as and for the purposes 35 shown and described.

3. The combination of the clip L, hook M N, the latch P R S, and a spring, V, substantially as shown and described, for the purposes 40 specified.

4. The improved hame-tug and trace-coupling, composed of the solid plate A, having perforations and annular flanges C, a plate, B, having a series of perforations adapted to admit the flanges C on the plate A, and a hook, 45 D, adapted to enter an opening in the end of the plate A, a leather covering on the plate A, having its edges covered by the plate B, a loop at the rear end, and a loop or clip at the front end, of the combined plates A and B and a clip having an expansible hook adapted to enter and engage the annular flanges C, fixed to the front end of a trace, as 50 and for the purposes stated.
